HOLDER FOR CLEANING PADS OR THE LIKE

Lawrence Stern, Woodmere, N. Y., assignor to
American Steel Wool Mfg. Co. Inc., New York,
N. Y.

Application January 20, 1936, Serial No. 59,825

1 Claim. (Cl. 15—154)

The present invention relates to holders for cleaning or scouring pads, or pad materials. Said holders are intended primarily for use in connection with steel wool scouring pads but 5 may be used with other pads.

One object of the invention is to provide a holder of the class described, constructed and arranged to obtain a distributed pressure over a substantial portion of the working surface of 10 the pad, when pressure is exerted on the holder in manipulating the pad.

Another object is to provide a holder for use especially with steel wool pads of triangular cross section.

15 Another object of the invention is to provide a holder of such construction that it may be readily secured to and removed from the pad.

20 A further object of the invention is to provide a holder which is inexpensive to manufacture and yet advantageous in construction and use.

Another object of the invention is the provision of a holder having integral pad clamping and handle portions made of wood or other heat insulating material.

25 The above objects of the invention and other objects which might hereinafter appear are realized by the embodiment of the invention hereinafter described in detail with reference to the accompanying drawing.

30 In the drawing:

Fig. 1 is a perspective view of the holder attached to a cleaning pad;

Fig. 2 is a sectional view on the line 2—2 of Fig. 1;

35 Fig. 3 is a plan view of the holder removed from the pad, showing the pad-clamping and handle members in pad-releasing position;

Fig. 4 is a sectional view on the line 4—4 of Fig. 3;

40 Fig. 5 is a fragmentary side view of the pad-engaging end of the holder.

Referring to the drawing in detail, there is shown a pad holder 10 comprising two relatively movable elongated members 12 having confront- 45 ing surfaces between which a pad or mass 14 of steel wool or other compressible material may be clamped. Said members 12 are preferably made of wood or other non-conducting material, and are connected at one end by a metal spring clip 16 which tends to separate the opposite ends 50 of the members 12. A slideable collar 18, constituted by a relatively rigid metal wire loop, encircles the clamping members 12 and is movable toward and away from the pad-engaging ends 55 of said members to releasably hold said members

in pad-clamping relation and to release said members to permit the removal of the holder from the pad. The pad 14 is preferably triangular in cross section and comprises a spirally wound ribbon of steel wool. 5

Each pad-clamping and handle member 12 is substantially rectangular in cross section and tapers in width from the portion thereof which engages the pad toward its end to which the spring clip 16 is connected forming a shouldered portion 20. Said shouldered portions are engaged by the arms 22 of the spring clip 16, said arms having inturned ends 24 which the received in openings 26 in the members 12 adjacent the shoulders 28 on said portions 20. As best shown in Fig. 4, the arms 22 of the clip 16 are disposed in grooves 30 provided in the outer surface of said shoulder portions 20. 10 15

At the end of the holder, adjacent the spring clip 16, members 12 are designed to provide confronting surfaces 32 disposed to extend in diverging relation against the pressure of said spring clip 16 when the collar 18 is moved toward the pad-engaging ends of said members to bring them into clamping relation. Accordingly, when 20 the collar 18 is moved toward the spring clip 16 to release the pad, said spring clip forces the adjacent end portions of the members 12 toward each other, bringing the surfaces 32 into contact with each other and separating the confronting surfaces 34, as shown in Fig. 3, to permit the removal of the holder from the pad. It will be observed that the confronting surfaces 32 of the members 12 are in angular relation to the confronting surfaces 34 and that said members have a fulcrum or pivotal bearing engagement on each other in the region 36 between said angularly related surfaces 32 and 34, the confronting surfaces of the members 12 being slightly curved to improve the fulcrum engagement 40 between said members. When the collar 18 is moved to bring the members 12 into pad-clamping relation, the arms 22 of the spring clip 16 separate somewhat but the inturned ends 24 are of such length as to remain in the openings 26. 45

An important feature of the present invention resides in constructing the members 12 in such manner that pressure exerted on the holder in manipulating the pad is distributed substantially uniformly over a relatively large surface of the pad. This is accomplished, in accordance with the present embodiment of the invention, by beveling the pad-engaging ends 38 of the members 12. By thus providing the members 12 with bevelled ends for engagement with the pad, the 50 55

relatively large cross sectional area of said members is further increased so that the pressure exerted on the holder, instead of being concentrated in a small portion of the pad, is distributed over a relatively large portion thereof and undue compressing of the pad material is prevented with the result that the pad retains its shape for a longer period of time and in general has a longer life. The provision of the 10 bevelled ends also causes the holder to be disposed in angular relation to the pad and thereby facilitates the manipulation of the holder. It will be understood that the term pad as used herein means any mass of cleaning, polishing, or 15 scouring material, or any other material or article with which the present holder may be used.

While I have shown the preferred embodiments of the invention, it will be understood that 20 certain changes in the construction and arrangement of parts may be made within the scope of the invention. Therefore, I do not wish to be limited to the precise construction herein shown or described, except as may be required by the appended claim or prior art.

Having described my invention, what I claim and desire to secure by Letters Patent is:

A holder of the class described comprising two relatively movable elongated members of substantially rigid material, said members having 5 confronting surfaces between which a pad may be held and adjacent flat plane end-surfaces at one end of the holder engageable on the pad to exert pressure thereon to force the pad against the object treated thereby, the flat plane end 10 surface of each of said members being substantially larger in area than the cross section of said member whereby to distribute the pressure exerted on said pad over a relatively large surface area thereof, said members being substantially straight from end to end and the ends terminating in said larger surfaces being bevelled whereby said members are inclined upwardly from the work-engaging surface of the pad when 15 said end surfaces are in engagement therewith and parallel to the work-engaging surface of the pad.
